UNITED STATES PATENT OFFICE.

RALEIGH I. KLIPSTEIN, OF DES PLAINES, ILLINOIS.

VALVE TAPPET AND THE LIKE FOR INTERNAL-COMBUSTION ENGINES.

Application filed July 25, 1924. Serial No. 728,125.

To all whom it may concern:

Be it known that I, RALEIGH I. KLIPSTEIN, a citizen of the United States, residing at Des Plaines, in the county of Cook and State of Illinois, have invented certain new and useful Improvements in Valve Tappets and the like for Internal-combustion Engines, of which the following is a specification.

10 This invention has to do with improvements in valve tappets and the like for the poppet valves of internal combustion engines, and has reference particularly to the means for adjusting the tappets with regard 15 to the valve stems or the rocker arms by which the valve stems are directly operated.

One object of the invention is to provide an adjustment of such a nature that a constant spring pressure may be exerted between the tappet and the valve stem or rocker arm, so that clearances between the various parts are entirely eliminated. In this way a very quiet operating construction will be provided.

25 Another feature in conjunction with the foregoing consists in the provision of means whereby the amount of spring tension just referred to can be adjusted. This will make it possible to insure quiet operation and at the same time will make it possible to so adjust the parts that the main valve spring will always effectively close the valve.

Another feature of the invention relates to the provision of a device which can be constructed as a unit and so that it can be readily set into place between the tappet and either the valve stem or the rocker arm, such units being self-contained and of compact and rugged form.

40 Other objects and uses of the invention will appear from a detailed description of the same, which consists in the features of construction and combinations of parts hereinafter described and claimed.

45 In the drawing:

Figure 1 shows a side elevation of the upper portion of an engine, having one of the devices of the present invention applied between the tappet and rocker arm thereof;

50 Fig. 2 shows a vertical section through the adjustment device of the present invention, on enlarged scale as compared with Fig. 1; and

55 Figs. 3 and 4 show cross sections on the lines 3-3 and 4-4 of Fig. 2, respectively, looking in the direction of the arrows.

In the particular construction illustrated in the drawing, the engine block is designated by the numeral 5. The construction illustrated is of the overhead valve type. There is, therefore, illustrated a poppet valve 6 in the cylinder head 7, said poppet valve having a stem 8 working through the guide 9 and reaching to the outside of the cylinder block, where the spring 10 works 65 against the collar 11 on the exposed portion of the valve stem so as to normally raise the valve into the closed position. The construction also includes a rocker arm 12 pivoted to the bracket 13 at the point 14 in accordance with well understood practice.

The tappet rod 15 reaches up at one side of the cylinder block from the cam shaft or tappet guide assembly to the rocker arm 12; or in the present case to the adjustment device designated in its entirety by the numeral 16. This adjustment device includes a cylindrical member 17, the upper end of which carries a lug 18 having its head 19 preferably rounded and of semi-spherical form. This rounded head engages a semi-spherically socket 20 in the rocker arm 12.

Secured to the lower end of the member 17 is a collar 21 having a neck 22 through which the tappet rod 15 is slidably passed. Within the member 17 is a relatively light spring 23 as compared to the main valve spring 10. The upper end of the tappet rod 15 works against the spring 23, and for this purpose a ball 24, preferably of hard steel, is placed in the lower end of the member 17 and carries the lower end of the spring 23. The convolutions of this spring 23 are quite close together, so that only a relatively small movement of the tappet rod 15 is necessary in order to take up the clearances between the convolutions. Thereupon the force from the tappet rod is directly exerted without further cushioning action by the spring.

Located in the upper portion of the member 17 is a head block 24 against which bears the upper end of the spring 23. This head block is connected to the member 17 or the lug 18, so that the force delivered thereto by the spring is immediately communicated to the head 19 and thence to the rocker arm.

In the particular construction illustrated, a small worm gear 25 is placed in the upper 110 end of the member 17, and bears against the head 18 thereof through the medium of a

number of balls 26 constituting a ball bearing. The block 24 has a threaded stem 27 which is threaded into the worm gear 25 so that by turning the worm gear the block 24 will be raised or lowered, provided it is not allowed to rotate. Such rotation of the block 24 is resisted by a pin 28 which is threaded through the wall of the member 17, and the inner end of which engages a vertical slot 29 in the block 24. After the vertical adjustment of the block 24 has been effected, the pin 28 can be tightened up so as to lock said block rigidly in place, in addition to the presence of other forces, tending to hold the same in place.

In order to turn the worm gear 25 for the above adjustment, I have provided a short worm 30 working in the upper portion of the member 17 and engaging the worm gear. This worm 30 has one end socketed in the member 17 at the point 31, and its other end 32 is provided with a slot for the reception of a screw driver. A plate 33 is secured to the outside face of the upper portion of the member 17 by a screw 34. This plate 33 overlies the end of the worm 30 but has an opening 35 in line with the slotted end of the worm, so that the screw driver adjustment can be easily made.

It will be noted that when in service the parts are so adjusted that the tappet rod is in firm contact with the ball 24 at its upper end, and with the cam shaft or tappet guide assembly at its lower end, the rocker arm 12 being at the same time in contact with the upper end of the valve stem 8 and with the upper end 19 of the lug 18. As a consequence there never exists any clearance between the parts, even when the operating cam is at its lowest position. At such time, however, the convolutions of the light spring 23 are slightly separated, as indicated in Fig. 2. Immediately upon the raising of the cam these convolutions are brought together and then the full lifting force is exerted through the medium of the unit.

It will be understood that a similar construction can be readily used at the lower end of a tappet rod, as, for example, in connection with the stems of valves which are to be raised when opened. I do not, however, deem it necessary to illustrate the various

other forms of construction which will readily suggest themselves to the user.

55

I claim:

1. As a new article of manufacture, a device for the purpose specified including a cylindrical member having a downwardly extending guide sleeve at its lower end for the accommodation of the upper end of a tappet rod, a ball within said member adapted to receive the thrusts of the upper end of said rod, an adjustment block within said cylindrical member above the ball, a spring between the adjustment block and ball, a threaded stem on the upper end of the adjustment block, a worm gear threaded on said stem, a ball bearing between said worm gear and the upper end of the cylindrical member, a worm extending across the cylindrical member and engaging the worm gear, whereby the position of the adjustment block may be varied by the adjustment of the worm, means for locking the adjustment block in adjusted position, and a hemispherical head on the upper end of the member, substantially as described.

70

2. As a new article of manufacture, a self-contained tappet member including a cylindrical element having an opening at its lower end for the accommodation of the upper end of a tappet rod or the like, an adjustment block within the cylindrical member above the position of said opening, a spring between the adjustment block and opening to transmit the thrust from the tappet rod to the block, means within the cylindrical element for adjusting the position of the adjustment block comprising a worm rotatably mounted within the upper end of the cylindrical member and a transverse screw for engaging said worm and journaled in the upper portion of the cylindrical member, a suitable connection on the upper end of the cylindrical member for the transmission of the operating force from the cylindrical member, and means in conjunction with the cylindrical member for retaining the spring in place therein and for retaining the adjustment block and the adjusting means in their adjusted position with respect to the cylindrical member at all times, substantially as described.
